SKEW ARCH SUPPORT

Harry L. McFeaters, New Castle, Pa., assignor to
Pennsylvania Engineering Corporation, a corporation of Pennsylvania

Application June 20, 1945, Serial No. 600,493

7 Claims. (Cl. 110—99)

1

This invention relates to inclined segmental arches and more particularly to means for supporting the inclined segmental roof arches of the ports of the hearth and uptakes of tilting open hearth furnaces.

In tilting open hearth furnaces, the end of each hearth port is separated or spaced from the adjacent end of the cooperating port of one of the regenerator uptakes. These port ends are protected by water cooled "chills" which are usually hollow metal members secured to the steel framework of the hearth and regenerators respectively for protecting the outer ends of the port structures. Spaces are left between the outer faces of adjacent chills so that the furnace hearth can be freely tilted between the ports of the regenerator uptakes.

Prior to this invention, it has been customary to support the skew bricks for the port roof arches of tilting open hearth furnaces by heavy steel channels; the channels for the hearth ports being secured to the hearth framework immediately below and in position to support the ends of the roof arches and those for the uptake ports to the framework of the regenerators immediately below and in position to support the ends of the regenerator roof arches.

Since these roof arches are usually inclined, it has been customary to incline these channels (the webs standing vertically) and to stack the skewback bricks for the different courses of the arches within the channels and on the lower flanges, with the backs of the bricks in contact with the webs of the channels and with skewback bricks for the lowest course of each arch resting against the adjacent chill for such port end. Since the chills take the thrust due to the inclination of the arch there is a tendency for the stack of skewback bricks to slide down the inclined channels. The chills are hollow, are usually made up of plate sections welded together, and do not provide satisfactory end abutments for heavy inclined arches.

An object of this invention is to produce improved supports for the ends of inclined segmental arches.

Another object is to produce improved supports for the ends of the inclined roof arches of the ports of tilting open hearth furnaces employing water cooled chills for the port ends.

A further object is to produce a pair of metal members for so supporting the ends of an inclined skew arch that each course of such arch is supported independently of the other courses and receives no end thrust from the courses thereabove.

2

A further object is to produce a pair of metal members for independently supporting the courses of an inclined skew arch.

These and other objects I attain by means of the structure described in the specification and illustrated in the drawings accompanying and forming part of this application.

In the drawings:

10 Figure 1 is an isometric perspective of a support member of this invention for supporting one end of a nine course inclined segmental arch;

Fig. 2 is a view similar to Fig. 1, but in this view the member is adapted to support one end of an inclined segmental arch comprising seventeen courses;

Fig. 3 is a fragmentary view in side elevation of the port roof at one end of the hearth of a tilting open hearth furnace and the roof of the co-operating uptake port of the furnace regenerator supported by means embodying this invention. This view by dot and dash lines shows portions of the furnace framework and one of the charging ports of the hearth, and illustrates the use of the support of Fig. 1 in supporting one hearth roof arch; the back of the support of Fig. 1 being shown. This view also illustrates the use of the support of Fig. 2 in supporting the roof of the regenerator uptake port co-operating with such hearth port; the view shows the back of the support of Fig. 2;

Fig. 4 is a top plan view of the near half of the structure of Fig. 3; the furnace framework shown by dot and dash lines being on the opposite side of the furnace from that shown in Fig. 3;

Fig. 5 is an isometric perspective of the near half of the structure of Fig. 3 looking in the direction of the arrow from the line V—V;

Fig. 6 is a view similar to Fig. 5 of the near half of the structure shown in Fig. 3, looking in the direction of the arrow from line VI—VI;

Fig. 7 is a more or less diagrammatic section taken on line VII—VII of Fig. 3 and illustrates the far side of the lowest course of the roof arch of the hearth port of Fig. 3;

Fig. 8 is a view similar to Fig. 7 and illustrates a portion of the far side of the lower course of the roof port of the regenerator uptake and is taken on line VIII—VIII of Fig. 3;

Fig. 9 is a side elevational view of a modified form of the support of Fig. 1; and

Fig. 10 is an end elevation of the support of Fig. 9 showing the top and bottom courses of an arch in dash lines.

55 The support members of this invention are secured to the steel structure of the furnace in

the same manner and in the same positions as the channels of the prior art, and are diagrammatically disclosed in Figs. 3 and 4 of the drawings.

In Figs. 3 and 4, support members 20 (only one being shown) for the hearth port roof arch comprising courses 21, are secured to the structural steelwork 22 of the furnace hearth immediately below the ends of such arch. Supports 23 (only one being shown) for the port roof arch (comprising courses 24) of the regenerator uptake are secured to the structural steelwork 25 of the regenerator immediately below the ends of such arch.

Each support member 20 is generally channel shaped, and is preferably formed as a unitary steel casting, with the end portions 26 and 27 extending at angles to the main or body portion thereof. Within the channel and taking the place of the lower flange of the main or body portion, I provide a series of steps or support surfaces 28 (in this case seven). The number of steps or support surfaces 28 corresponds to the number of courses 24, minus the end courses; the skew bricks for the end courses being supported on the lower flanges of the angled end portions.

Support members 20 and 23 are secured in inclined position, as disclosed in Figs. 3, 5 and 6 so that the upper faces of the steps or support surfaces and said lower flanges lie in parallel horizontal planes. Steps 28 and flanges 29 and 30 form horizontal support surfaces for independently supporting the skewback bricks for the arch courses.

Each support 23 for the roof arches of the ports of the regenerator uptakes is provided with 15 steps or support surfaces 31, since there are seventeen courses in each of these roof arches; the skew bricks for the upper and lower end courses being supported on the lower flanges 32 and 33 of the angled end portions 34 and 35, respectively of the support members. Steps 31 and flanges 32 and 33 form horizontal support surfaces for independently supporting the skewback bricks for courses 24.

The left-hand portions of Figs. 3 and 4 disclose opposite halves of the roof arch for the port at one end of the tilting hearth of an open hearth furnace, while the right-hand portions of Figs. 3 and 4 disclose opposite halves of the roof arch for the co-operating port of the regenerator uptake. Part of the steel framework for the hearth and regenerator and one of the charging ports 36 for the hearth are shown by dot and dash lines. In Fig. 3, this steel framework is shown on the far side of the furnace, while in Fig. 4, it is shown on the near side.

Figs. 5 and 6 disclose the skewback bricks 37 and 38 supporting the arch courses on the support surfaces or steps of the support member. These skewbricks are shown resting on the support steps and the lower flanges of the end portions.

It will be apparent from the fact that each course of each arch has its own horizontal complementary support surfaces for its skew bricks that such course will produce no thrust against the next lower course. Each course of each arch is supported independently of the other courses and for this reason, there will be no end thrust on the chills at the lower ends of the ports, since sliding movement in a downward direction is prevented by the complementary hori-

zontal steps which support each pair of skewbricks independently of the other pairs.

Each port roof arch, whether for the hearth or the regenerator uptake, may be a segment of the frustum of a cone or the segment of a cylinder, but whichever type, the arch will be sloped or inclined at an angle to the horizontal.

In the modified form of support member of Figs. 9 and 10, steps 39 extend horizontally. The supporting surface 40 of each step is oblique and has the same inclination as a skewbrick would have, if employed. In other words, inclined face 40 parallels the end face of the end brick of the course supported thereby in co-operation with the complementary surface on the support member for the other end of the arch. The angle or inclination of each support surface 40 differs from the angle or inclination of every other support surface 40 and such angle or inclination parallels the outer end of the end brick of each course of the arch. When the modification of Figs. 9 and 10 is employed, skewbricks are unnecessary.

It will be apparent that the support members of this invention whether designed to support skewbricks or to function without skewbricks may be made hollow for the purpose of being water cooled.

Having thus described my invention, what I claim as new and desire to secure by Letters Patent is:

1. In a tilting hearth regenerative furnace having each of the co-operating ports of the hearth and regenerators roofed by an arch having its longitudinal axis inclined to the horizontal, comprising multiple contiguous courses extending transversely of such axis and having their lower extremities stepped, means for supporting each course of each such arch independently of the other courses thereof, such means comprising a pair of spaced metal members secured to the furnace structure immediately below the lower extremities of such arch courses; each such member comprising a unitary structure provided with a stepped series of support surfaces and having its longitudinal axis inclined to the horizontal, each support surface of one member of such pair co-operating with the complementary support surface of the other member of such pair in supporting an arch course.

2. A structure as defined in claim 1, in which the support surfaces are horizontal.

3. A structure as defined in claim 1, in which each metal member is generally channel-shaped and the support surfaces are horizontal.

4. A structure as defined in claim 1, in which the support surfaces are inclined.

5. A structure as defined in claim 1, in which the support surfaces are inclined and arranged to parallel the lower faces of the end bricks of the arch courses to be supported thereby.

6. In a tilting hearth regenerative furnace having each of the co-operating ports of the hearth and regenerators roofed by an arch having its longitudinal axis inclined to the horizontal, comprising multiple contiguous courses extending transversely of such axis and having their lower extremities stepped, a pair of metal members secured to the furnace structure immediately below the lower extremities of each such arch, each such member comprising a unitary structure provided with a stepped series of support surfaces and having its longitudinal axis inclined to the horizontal, each support surface of one such member co-operating with the complementary

support surface of the other member of each pair in supporting one course of one such arch.

7. In a tilting hearth regenerative furnace having each of the co-operating ports of the hearth and regenerators roofed by an arch having its longitudinal axis inclined to the horizontal, comprising multiple contiguous courses extending transversely of such axis and having their lower extremities stepped, a pair of metal members secured to the furnace structure immediately below the lower extremities of each such arch, each such member comprising a unitary structure provided with a stepped series of support surfaces corresponding in number to the number of courses in the arch being supported; each support surface of one such member of a pair co-operating with the complementary support sur-

face of the other member of such pair in supporting one course of one such arch.

HARRY L. McFEATERS.
